GOVERNOR FOR STEAM-TURBINES.

1,059,387.

Specification of Letters Patent. Patented Apr. 22, 1913.

Application filed October 7, 1908. Serial No. 456,563.

To all whom it may concern:

Be it known that I, WERNER Ott, citizen of the Republic of Switzerland, residing at Pilsen, in Bohemia, Austria-Hungary, have 5 invented certain new and useful Improvements in Regulating Apparatus or Governors for Steam or Gas Turbines, of which the following is a specification.

This invention relates to regulating apparatus or governors for steam or gas turbines of the type comprising a part driven by a high pressure medium and one or more other parts driven by a medium at a lower pressure. In such high and low pressure turbines, the low pressure portion of which is driven say for example by the exhaust steam from high pressure steam engines of any kind working intermittently or continuously and at a definite counter pressure it is necessary, during the time in which such engines do not supply sufficient steam for driving the low pressure portion, to supply the high pressure valve or the turbine stages of higher steam pressure with live steam in 25 order that the drop in the work caused by the lesser quantity of steam may be equalized. For this purpose it is necessary that both the live steam regulating valve as well as the regulating valve for the exhaust steam should be placed under the influence of the speed regulator or governor and in addition to this both such valves must be placed under the influence of an apparatus which is acted upon by the pressure of the 30 exhaust steam from the primary engine and which, when the pressure of the exhaust steam drops, closes the low pressure valve more and more and correspondingly opens the high pressure valve so that the load inside the various stages of the whole turbine is distributed to correspond to the volume of exhaust steam present.

Now the object of the present invention is to provide improved governing mechanism suitable to effect this purpose and whereby it is insured that even in this combined regulation the position of the speed governor is only dependent upon the load of the machines driven by the whole turbine, 50 that is to say is quite independent of the distribution of the total load over the several stages of such whole turbine. This is in particular unconditionally necessary when the turbine is coupled to an alternating current or rotary current generator and the

electrical machines are connected up to other generators, as in such arrangements the number of revolutions and consequently also the position of the regulator must be kept constant when there is a definite load on the whole turbine.

Governors embodying this invention are illustrated by way of example in the accompanying drawings.

Figure 1 shows partly in side elevation 65 and partly in section a construction of governor mechanism in which the speed regulator and the pressure regulator act directly upon the valve mechanism. Fig. 2 is a dia- 70 grammatic representation of an arrangement in which the speed regulator acts upon the valve mechanism through a servo-motor, while the pressure regulator acts directly upon it. Fig. 3 is a diagram of an arrangement in which the speed regulator and the 75 pressure regulator both act upon the valve mechanism through the agency of the servomotors. Figs. 4, 5 and 6 are similar dia- 80 grams indicating modified constructions.

The principle of the present invention 85 will be understood by reference to Fig. 1 in which A indicates the regulating valve for the low pressure steam, B the regulating valve for the high pressure steam, and C the speed regulator. The steam passes through the valves in the manner indicated by the arrows. The speed regulator C acts upon a lever 1 through a lever 3 mounted to rock about a pivot 2 and connected by a rod 5 to the lever 1 at an intermediate point 90 4. A rod 6 is connected with one end b² of the lever 1 and transmits its movement to a lever 7 rigidly mounted upon a rocking pin 8 pivoted in the low pressure throttle valve casing 12. A lever 13 within the casing 12 is also rigidly fixed on the rocking pin 8 and pivotally connected at 9 to the low pressure steam throttling device comprising a stem carrying two disk valves 10 and 11. The movements of the opposite end b of the lever 1 are transmitted to the high pressure throttle valve 15—16 in a similar way by a rod 18 and the levers 14 and 19. The high pressure regulating valve 15—16 is pressed constantly against its seat by a spring 17 inclosed in the valve casing so that the adjacent end b of the lever 1 is normally held in its lowest position and constitutes a relatively fixed point about 105 which the lever 1 can oscillate. Instead of a 110

spring 17 a weight may be employed. A piston 20 is arranged to move easily but in an air tight manner within the casing of the low pressure steam regulating valve A, the underside of the piston being exposed to the pressure of the incoming exhaust steam and the top of the piston being acted upon by an adjustable spring 21. The piston 20 is provided with a centrally arranged stem 20^a, which, when the piston is in its lower position, presses down the stem of the double seat valve 10—11, while, when the piston is in its highest position the valve is completely released and is therefore only 15 under the influence of the speed regulator through the rods and levers heretofore mentioned.

The apparatus works in the following way: So long as sufficient exhaust steam is 20 available from the primary engine for the purpose of taking over the entire duty of the whole turbine, the piston 20 will be forced up by the pressure of the exhaust steam and, as described, completely releases the low pressure valve 10—11. The spring 17 on the other hand, forces the high pressure valve 15—16 down onto its seat so that the end b of the lever 1 is in its lowest position and constitutes the center of oscillation of the lever and, on the movement of the regulator C out of its highest position indicated by 1' into the lowest position indicated by 1'', the lever 1 will be shifted from its position 5' to the 25 position 5'' and the low pressure valve 10—11 will pass from the completely closed position into the position of maximum opening. When the quantity of exhaust steam is sufficient the full regulator stroke 1' to 30 1'' therefore corresponds to the transition of the load on the turbine from zero load to full load.

The conditions shown in Fig. 1 correspond to the position of the regulation for 45 a mean load, in which case the rods and levers are situated in a central position. If now, with this load on the turbine, the supply of exhaust steam decreases to such an extent that it is no longer sufficient for the 50 duty of the turbine, the pressure of the incoming exhaust steam falls, the piston 20 is relieved of load and is thereupon moved downwardly by the spring 21 until 55 equilibrium is again established between the spring pressure above and the steam pressure below. Immediately the piston spindle 20^a strikes against the spindle of the regulating valve 10—11, this valve, on the further downward movement of the piston 60 20, will be forced downward with considerable force, that is to say will be closed more and more. At the same time the end 65 of the lever 1 will be forced downwardly and the lever caused to rock about the point 70 45, which, with a constant load on the en-

gine producing a constant number of revolutions of the regulator C, constitutes a fixed point. This movement causes the high pressure valve to be opened to an extent that gradually increases in proportion 70 as the cross sectional areas of passage in the low pressure valve become reduced. It is 75 obviously assumed here that the spring 21 is able to overcome the power of the spring 17 and that on the other hand the speed 80 regulator C is sufficiently powerful to take up the back thrust of the valve gear. The downward movement of the piston 20 continues until the withdrawal of exhaust steam is caused to correspond by throttling 85 to the supply of steam from the primary engines so that the pressure can no longer fall. If for example the supply of exhaust steam ceases entirely the pressure falls until the valve 10—11 is closed, that is to say until 90 the lever 1 has been rocked on the pivot 4 into the position 5', 6'. The high pressure part of the turbine or the high pressure steam alone has now accordingly taken over the momentary work of the whole turbine, 95 without any movement of the position of the speed regulator being necessary. The load has therefore been transferred, at a perfectly constant number of revolutions, from the low pressure turbine part to the high 100 pressure turbine part. In the position 5' or in any other desired position of the end 105 b² of the lever 1 between 5' and 5'', the lever end b², in contradistinction to the previously described case and with a change in 110 load which is connected with a change in the number of revolutions, constitutes a point of oscillation for the lever, so that now so long as the pressure of the low pressure steam remains constant when the speed 115 regulator is moved it is the movement of the high pressure valve only which is controlled, during which time that of the low pressure valve remains constant; in the final 120 position 5' of the low pressure valve rods 110 and levers in particular the transition of the load on the turbine from zero to full load again corresponds to the movement of the regulator from its highest position 1' to its lowest position 1''. It is easy to prove 115 that the position of the regulator is only dependent upon the load on the turbine in every intermediate position of the piston 20 and is therefore quite independent of the 120 pressure of the exhaust steam.

The remaining figures of the drawings illustrate, by way of example, how the above described conditions can be fulfilled by the use of a servo-motor.

In the arrangement shown in Fig. 2, in 125 which the speed regulator C does not act directly upon the valve mechanism but through the agency of a servo-motor, while the pressure regulator, as in Fig. 1, acts directly on the valve mechanism, the regu- 130

lator C acts, through levers 3 and 22 and rod 5^a connecting said levers upon the controlling valve 24 of the servo-motor, which by means of the pipes 25, 26 and 27, 28 communicates with the servo-motor cylinder 29. The piston 30 of the servo-motor acts through the connecting rod 31, lever 1 intermediately pivoted thereto, rod 6, and levers 7 and 13 upon the low pressure regulating valve A, or by means of rod 18 and levers 14 and 19 upon the high pressure valve B and the regulation is accomplished in a manner exactly similar to that shown in Fig. 1. After the controlling valve 24 has been moved over to an extreme position by the movement of the piston of the servo-motor it will be brought back again into its central position by the lever 22, in the usual way.

As shown in Fig. 3 both the pressure regulator as well as the speed regulator may be arranged to act upon the valve mechanism by means of servo-motors. In this case the valve mechanism is influenced by the speed regulator in a manner exactly similar to that shown in Fig. 2. The pressure regulating piston 20 is, in comparison to the former constructional example, still only a receiver, but transmits its movement through the rod 32 attached to the piston and lever 35 to the controlling valve 36, through which the servo-motor is worked. In this case also the servo-motor piston 38 is not rigidly connected to the regulating rods and levers, but leaves them completely free as long as the accumulator pressure is sufficiently high, which in this case corresponds to the lowest position of the servo-motor piston 38. The controlling valve 36 is not returned by the piston rod of the servo-motor, but by a connecting rod 34 attached to the levers 7 and 35. In this way the controlling valve 36 of the pressure regulator is kept constantly in motion by the speed regulation device and the necessity of moving it back to its central position after each operation is thus avoided. As long as the accumulator pressure is sufficiently high the controlling valve 36 is moved upwardly out of its central position in every position of the speed regulator so that the upper side of the piston of the servo-motor piston 38 is under oil pressure and completely frees the piston rod 39 from the valve mechanism. If the pressure in the accumulator falls the controlling valve is gradually brought into its central position and only moved downwardly from the central position on a further fall in pressure so that the under side of the servo-motor piston 38 is then under oil pressure and is thrust upwardly thereby. As however the return of the controlling valve is not directly effected by the servo-motor, the underside of the piston of the servo-motor remains under oil pressure until the rod 39 strikes against

the lower end of the rod 6 of the controlling mechanism and forces the latter upwardly and thereby firstly acts upon the valve mechanism in the manner described and secondly moves the valve 36 into its central position.

In the constructional form shown in Fig. 4 the regulator lever 1 is again connected to the speed regulator C at the point 4 through the rod 5 and lever 3, but the controlling valves 36, 24 for the servo-motors 37, 29 of the low pressure valve A and the high pressure valve B respectively are attached directly to opposite ends of the lever 1 by rods 23 and 33. In this construction the casings 40, 41 of the controlling valves are themselves movable and are connected to the piston rods 43 and 43^a of the servo-motor cylinders 37 and 29 by levers 42 and 44 respectively. By means of a blade spring 46 or some other suitable spring or weight adapted to press the end b of the lever 1 downwardly toward its lowest position the lower end of the servo-motor cylinder 29 is normally under oil pressure and the piston of the servo-motor is accordingly in its highest position, that is to say the high pressure regulating valve B is in its closed position. The end b of the lever 1 at such times therefore constitutes the point of oscillation of the lever 1 and the movement of the speed regulator is transmitted to the low pressure valve A in the following manner: When the sleeve of the speed regulator moves upwardly the controlling valve 36 will first be moved downwardly, so that by means of the flexible connecting pipes 47-48 and 49-50 respectively, the underside of the servo-motor cylinder 37 will be put into communication with oil under pressure and the upper side with the exhaust pipe. The piston 38 of the servo-motor cylinder 37 will therefore be forced upwardly as will also the connecting rod 6 pivoted to the lever 7 of the low pressure valve 10-11, so that said valve will be moved toward its closing position and, by means of the lever 42, the casing 40 of the controlling valve will be drawn downward, the result of which will be the cutting off of the oil passages and therefore the return of the valve gear. The piston 18^a which is located in a pressure regulating cylinder 51 is loaded by the pressure of the spring 19^a on the one side and on the other side is in communication with the accumulator pressure by the branch 52. So long as the accumulator pressure is above a certain amount, the piston 18^a being raised, its rod 45 remains off the end b² of the rod 23, and thus the controlling valve 36 is only subjected to the action of the governor C through the levers 3, 5 and 1. But when the accumulator pressure falls, the rod 45 sinks down until it comes into contact with the end b² of the rod 23. The controlling valve 130

36 is operated in accordance with the variations of the accumulator pressure, and the lever 1 is moved about its pivot point 4, the low pressure valve being thus more nearly closed and the high pressure valve more widely opened. In this construction the casings of the controlling valves 36, 24 of the servo-motor are provided with eyes for pivotal attachment to the rods connecting them to the levers 42 and 44 respectively.

In the constructional form shown in Fig. 5 there are mounted upon rods 53 and 54 of the low pressure regulating valve A and the high pressure regulating valve B, respectively, pistons 38^a and 30^a, which are subjected to the action of springs 55, 56. Above the pistons oil under a definite pressure is admitted through branches 57, 58 and the supply is regulated by the rigidly adjusted throttling cocks 59 and 60 and the exhaust by means of throttling cocks 63 and 64 respectively worked by the speed regulator C and the members 3, 5, 1, 6, 18 and levers 7^a and 14^a attached to the respective cocks 63 and 64. The end b of the lever 1 is constantly pressed downwardly by a spring 17^a and the cock 64 thereby closed, so that the exit of the oil under pressure is prevented and the piston 30^a is forced downwardly by the pressure of the oil and the high pressure valve B thereby closed. The lever end b therefore forms the point of oscillation for the lever 1 and the speed regulator acts only upon the low pressure regulating valve in such wise that when for example the number of revolutions drops the cock 63 is opened to a greater extent, whereby the pressure of the oil above the piston 38^a decreases and the valve A is opened to a greater extent by the spring 55. In addition to this a pressure regulating apparatus 51 is provided, the construction of which can be readily understood from the previous description without further explanation. 52 is the branch for connection to the source of the exhaust steam and it will be seen that on the decrease of the accumulator pressure the cock 63 and thereby the low pressure valve A is closed more and more and on the other hand the cock 64 and thereby the high pressure valve B will be opened to a greater extent. This arrangement therefore again insures that less exhaust steam and more live steam will be used.

Fig. 6 is a diagram illustrating the way in which the apparatus shown in Fig. 1 can be modified to operate three or more valves. The actuating levers 7 and 75 of the respective low pressure valve A and the intermediate pressure valve D are connected by rods 6 and 76 to a rocking lever 65, the pivotal point 66 of which is suspended by the rod 67 from the end b² of the lever 1. The pivotal point 4 of this lever is attached by means of the rod 5 and lever 3 to the speed

regulator C, while at the end b of lever 1 the actuating lever 14 of the high pressure valve B is connected by a rod 18 to the lever 1. The high pressure valve is pressed against its seat by the spring 17^b so that it is normally closed. The pistons 20^b and 68 of the valves A and D are loaded on the one hand by springs 55^b and 69 and on the other hand are subjected to the steam pressure of the corresponding stages through the branches 52^b and 70. If there is enough exhaust steam of the lowest pressure available and on the other hand little steam of intermediate pressure the valves D and B will be closed by the springs 69 and 17^b so that the end d of the lever 65 will become the point of oscillation and the speed regulator C will act only upon the low pressure valve A. If then the pressure of the intermediate steam pressure rises the valve D will be slightly opened whereas the valve A will be slightly closed. It is assumed here also that the speed regulator C is in a position to take up the back thrust arising from these spring forces, which can be attained at all times by the interposition of servomotors. In this manner more intermediate pressure steam will be withdrawn in the new position, which corresponds completely to the requirements for when enough intermediate pressure steam is available from any engine it is more suitable to the purpose to utilize this intermediate pressure steam and to let the low pressure steam go. It can easily be deduced from what has been hereinbefore stated that on the interruption of the supply of low pressure steam the end d² of the lever 65 becomes the point of oscillation of said lever and when the speed regulator is moved it only controls the intermediate pressure valve D. If both the source of intermediate pressure steam and the source of low pressure steam fail, either wholly or partially, the power of the spring 17^b will be overcome by the combined action of the powers of the springs 55^b and 69 and by this means the high pressure regulating valve B will be correspondingly opened.

Claims:

1. A regulating apparatus for engines, comprising a high pressure induction valve and a low pressure induction valve, a speed regulator acting on said valves separately and never simultaneously, and a pressure regulator acting directly on only one valve.
2. A regulating apparatus for engines, comprising a high pressure induction valve and a low pressure induction valve, a speed regulator connected to both valves for operating either independently, a pressure regulator operated by low pressure exhaust steam for automatically opening and closing one or both of said valves, the movements depending on the change of load and change of pressure of exhaust steam, and auxiliary

- apparatus controlled by said speed and pressure regulators for varying the volume of steam passing through said valves.
3. A regulating apparatus for engines, comprising a high pressure induction valve and a low pressure induction valve, a speed regulator connected to both valves, a pressure regulator acting on only one valve, and a connection between both valves for moving 10 the other valve when the former valve is moved by the pressure regulator.
4. A regulating apparatus for engines, comprising a high pressure induction valve and a low pressure induction valve, a pressure regulator acting on only one valve, and a speed regulator acting either on the low pressure or on the high pressure valve independently, according to the position of the pressure regulator.
- 20 5. A regulating apparatus for engines, comprising a high pressure induction valve, and a low pressure induction valve, a speed regulator connected to said valves but never operating both valves simultaneously, a pressure regulator acting directly on the low pressure valve, and means for interrupting the action of the pressure regulator on the low pressure valve so long as the pressure of the low pressure steam is sufficient.
- 25 6. A regulating apparatus for engines, comprising a high pressure induction valve and a low pressure induction valve, a speed regulator acting on said valves separately and never simultaneously, a pressure regulator acting directly only on the low pressure valve, means for interrupting said action when the pressure of the low pressure steam is sufficient, and means for closing the high pressure valve when the low pressure valve is not operated by the pressure regulator.
- 35 7. A regulating apparatus for engines, comprising a high pressure induction valve and a low pressure induction valve, a speed regulator connected to said valves but never 40 operating both valves simultaneously, a pressure regulator operated by low pressure exhaust steam and acting directly only on the low pressure valve, a connection between both valves for causing the movement of the high pressure valve when the low pressure valve is moved by the pressure regulator, means for causing the movement of the pressure regulator on the low pressure valve to cease so long as the pressure of the exhaust 45 steam is sufficient, and means for closing the high pressure valve when said action ceases.
- 50 In testimony whereof I have hereunto set my hand in presence of two subscribing witnesses.

WERNER OTT.
